TUBE

David H. Sloan, Pittsburgh, Pa., assignor to Westinghouse Electric Corporation, East Pittsburgh, Pa., a corporation of Pennsylvania

Application March 17, 1945, Serial No. 583,257

16 Claims. (Cl. 315—5)

1

This invention relates to an ultra-high-frequency tube and has particular relation to a tuning device for an ultra-high-frequency tube.

An ultra-high-frequency tube of the resonatron type is disclosed in my copending applications, Serial Nos. 526,882 and 526,883, filed on March 17, 1944, and assigned to the Westinghouse Electric & Manufacturing Company. Application 526,882 was patented January 18, 1949, as Patent Number 2,459,593, and application 526,883 was patented October 19, 1948, as Patent Number 2,451,987. The tube so disclosed comprises a pair of evacuated, cavity resonators adapted to have electromagnetic field oscillations of a high frequency established therein. The resonators are of a generally cylindrical shape and are mounted coaxially, the first resonator being positioned within a coaxial cylindrical reentrant protuberance in the second resonator. A generally cylindrical cathode of shorter length than the first resonator is positioned coaxially within the first or cathode resonator. An anode, also having a generally cylindrical form, is mounted within the second or anode resonator and encircles the cathode. Grid-like structures are formed in the adjacent walls of the two resonators, to permit electrons to flow radially from the cathode to the anode.

In this tube of my copending applications, the grid in the wall of the cathode resonator is known as the control grid. It is insulated from the cathode in that there is no metallic path for a flow of current therebetween. The grid in the wall of the anode resonator is, of course, in the wall of the protuberance and is known as the accelerating grid. It is insulated from the anode in that a complete metallic path for the flow of current therebetween is not present. Different direct current voltages are then impressed between the anode and cathode, accelerating grid and cathode, and the control grid and cathode.

The end of the reentrant protuberance is adjacent the end of the anode resonator to establish a capacitance therebetween and to insulate the accelerating grid from the anode, the anode resonator is formed in two parts. Then the anode resonator may be tuned by moving the two parts with respect to each other, to vary the capacitance between the end of the protuberance and the adjacent end of the anode resonator.

The resonatron tube operates generally as a tuned-plate, tuned grid class C oscillator, with the cathode resonator in the control grid-cathode circuit and the anode resonator in the anode or plate circuit. The two resonators are tuned to

substantially the same frequency and each is designed to have a principal mode of oscillation in which the electric field is substantially parallel to the electron path between the cathode and anode and the field within the resonators have a definite phase relationship, preferably with the field voltage of the cathode resonator lagging by an amount of the order of 90° behind the field voltage of the anode resonator. Relatively high, positive direct-current voltages between the anode and cathode and between the accelerating grid and cathode tend to liberate electrons from the cathode; but the control grid, while originally at a zero voltage, has a negative voltage during operation such that a group of electrons are liberated from the cathode only during the peak portion of each half-cycle of the field in the cathode resonator in which that field tends to aid in effecting liberation of the electrons and movement thereof toward the anode. Thus, sharp pulses of electrons are liberated at regular intervals from the cathode.

The liberated electrons first receive energy from the field of the cathode resonator as well as the direct-current voltage fields between the accelerating grid and cathode and the anode and cathode. As the liberated electrons move through the cathode resonator, their movement is greatly accelerated by the strong accelerating grid-cathode field. The speed of the electrons is such, with respect to the spacing of the elements, that the electrons cross the field of the anode resonator while that field is in a direction opposing their motion. As a result, the electrons give up energy to the field of the anode resonator to generate the desired oscillations therein. A portion of the power developed in the anode resonator is fed back to the cathode resonator, to maintain the desired oscillations therein. The remaining power is extracted from the anode resonator by some means such as a coupling loop and is supplied to an output transmission line.

A tube constructed in accordance with the teachings of my aforesaid copending applications operates quite satisfactorily in many systems. However, it has been found that in such a tube the Q, defined as the ratio of energy stored to the energy dissipated, of the anode resonator is too high for some systems. In addition, the maintenance of the anode and the accelerating grid at different potentials introduces complications in the structure of the anode resonator. The use of a quarter-wave choke arrangement between two parts of the anode resonator to insulate the anode from the accelerating grid and

permit varying the capacitance for tuning, makes it necessary in the prior tubes to provide an additional chamber enclosing the anode resonator to permit the resonator to be evacuated. There was also a leakage of a certain amount of power into this outer chamber through various necessary openings.

Since the anode and the accelerating grid, and consequently the water pipes for cooling the accelerating grid and anode, as well as the output coupling are at a high direct-current voltage in the prior tubes, further difficulties are encountered in mounting and properly insulating the tube for operation. The proper insulation is, of course, imperative to avoid injury to those operating the apparatus.

It is, accordingly, an object of my invention to provide a new and improved tube of the resnatron type.

Another object of my invention is to provide a novel tube of the resnatron type, having a new and improved tuning arrangement.

Still another object of my invention is to provide a new and improved tuning arrangement for a cavity resonator.

A further object of my invention is to provide a new and improved tube of the resnatron type in which insulation difficulties, in connection with the mounting thereof, are eliminated.

A still further object of my invention is to provide a novel tube of the resnatron type, having a greatly simplified and more rugged construction.

In accordance with my invention, I have discovered experimentally that a resnatron tube may be operated with the accelerating grid and the anode both maintained at the ground potential with the cathode being highly negative with respect thereto. This is contrary to the prior experiences of which I am aware of those skilled in the construction and operation of a tube of this type. With the anode and accelerating grid at ground potential insulation difficulties upon mounting of the tube are avoided. In addition, the anode resonator may be of a rugged construction, in which the accelerating grid and the anode are metallically interconnected. Consequently the large additional vacuum-tight structure surrounding the anode resonator may be eliminated as the anode resonator may itself be made vacuum-tight.

By my invention, the Q of the anode resonator is substantially reduced by a new tuning arrangement. Tuning is accomplished by the provision of movable short-circuiting contact means within the anode resonator and surrounding the reentrant protuberance. The contact means has a sliding contact with the side wall of the protuberance and the outer side wall of the resonator to establish a short circuit therebetween at any desired point. The contact means are liquid-cooled and are movable in a direction substantially parallel to the axis of the tube, by a manually adjustable apparatus which extends outside the anode resonator. The movement of the contact means to change the location of the short circuit, causes a variation in the tuning of the resonator. As is discussed in detail hereinafter, the tuning arrangement reduces the Q of the anode resonator by reducing the energy stored by approximately thirty percent.

The novel features of my invention are set forth with more particularity in the appended claims. The invention itself, however, with respect to the details of operation and construc-

tion, as well as further advantages and objects thereof, may be best understood from the following description of a specific embodiment, when read in connection with the accompanying drawings, in which:

Figure 1 is a cross-sectional view of a resnatron tube, in accordance with my invention;

Fig. 2 is a partial view, in cross-section, taken along lines II—II of Fig. 1;

Fig. 3 is a detailed sectional view of a portion of the contact means; and

Fig. 4 is a partial view, in section, taken along lines IV—IV of Fig. 1.

As shown in Figure 1, the tube comprises an anode resonator 5 and a cathode resonator 7. The anode resonator 5 is formed of a hollow, generally cylindrical, metallic body 9 having a generally cylindrical coaxial reentrant protuberance 11 extending from one end thereof.

The cathode resonator 7 is mounted coaxially within the reentrant protuberance 11 of the anode resonator 5. The cathode resonator 7 comprises a metal cylinder 13, open at one end, with a cathode unit 15 extending into that open end.

The cathode unit 15 includes a plurality of filament wires 17 arranged to form a generally cylindrical cage-like cathode 19 about the axis of the cathode resonator, a tubular cathode mounting 21, and a pair of tubular members 23 and 25 surrounding the mounting 21 and arranged for cooperation with cylinder 13 to form quarter-wave-length chokes closing the open end of the cathode-resonator cylinder 13. A small vacuum tight chamber 27 is secured to the bottom of body 9 over the end of the cathode resonator to seal the tube.

The mounting 21 for the cathode 19 includes leads for conducting heating current to the filament wires and applying a direct-current voltage thereto, as well as conduits for cooling the cathode unit which are not shown. The cathode resonator 7 may be readily tuned by adjusting the handwheel 29 at the bottom of the tube which effects a vertical movement of capacitor plates 31 mounted on the end of a tuning rod (not shown) which extends through the center of the cathode mounting 21 to the upper end of the cathode resonator. These details are fully described and illustrated in the aforesaid copending applications.

An anode 33 is supported from the body 9 of the anode resonator 5 within the annular space defined between the side wall of the reentrant protuberance 11 and the outer side wall of the body 9 and encircles the cathode 19. The anode 33 is a ring like structure formed of two ring members 35 and 37. The first ring member 35 encircles the cathode 19 and is of approximately the same height as the cathode. The second ring member 37 surrounds the first ring member 35 with a space between the inner diameter of the second ring member 37 and the outer diameter of the first ring member 35. Flanges 39 and 41 at opposite ends of ring members 35 and 37, respectively, extend over the space between the first and second ring members 35 and 37 so that a passageway 44 for cooling fluid is formed through the anode. Inlet and outlet pipes 43 and 45 communicating with the passageway 44 are adapted to be connected to a supply line for cooling fluid, such as water.

The surface of the first ring member 35 of the anode which is facing the cathode, is provided with a series of straight, crosswise grooves 47 having a semi-circular cross-section, there being one

groove radially opposite each filament wire 17 of the cathode 19. These grooves are shaped to trap the electrons provided by secondary emission when other electrons strike the anode. The trapping of the secondary electrons is aided by the flanges 39 and 41 which extend over the ends of the grooves and have an inner diameter less than that of the first ring member 35. Of course, the grooves 47 need not necessarily be semi-circular in cross-section as other shapes, such as V-shaped grooves, may be used satisfactorily. In addition, other anode structures may be used so long as they provide a good trap for secondary electrons, for reasons set forth hereinafter.

The adjacent walls of the cathode and anode resonators 7 and 5 between the cathode 19 and the anode 33, that is the walls of the cylinder 13 and protuberance 11, are provided with a plurality of openings therein, so that grids 49 and 51 are formed through which electrons may pass from the filament wires 17 to the anode 33. The grid 49 in the wall of the cathode resonator is known as the control grid, and the wall containing the grid is arranged to be cooled by a cooling-fluid, such as water, provided through suitable pipes 53 and 55. Details of this cooling arrangement may be found in my copending applications.

The grid 51 in the wall of the anode resonator 5 is, of course, in the wall of the reentrant protuberance 11. The reentrant protuberance is made up of a metal wall with a plurality of cooling pipes 57 against the running vertically along the wall, the pipes 57 being spaced about the wall so that a space between adjacent pipes is radially opposite each filament wire 17. Consequently, the accelerating grid 51 may be provided by a gap in the metal wall with the spaced cooling pipes 57 and the edges of the gap forming the grid. If desired the pipes 57 may be bent slightly toward the control grid 49 at the accelerating grid position to increase the accelerating effect. The pipes 57 are connected to conduits which in turn are to be connected to the cooling fluid supply.

A plurality of feedback coupling wires 59 are attached at one end to the cathode unit 15 in the cathode resonator 1 and extend radially through suitable openings in the walls of the cathode resonator 1 and the reentrant protuberance 11 into the anode resonator 5. The end portion of each coupling wire 59 within the anode resonator is curved at substantially right-angle, to form a conducting member adjacent and parallel to, but spaced from, the anode 33. Each coupling wire, in effect, provides a capacitor connected between the anode 33 and cathode 19.

As explained in my aforesaid copending applications, the two resonators are designed so that their electric field vectors are along radial lines. Consequently, alternate points of minimum and maximum voltage appear along the length of the cathode unit within the cathode resonator. The coupling wires 59 are preferably connected to the cathode unit at a point of maximum voltage with respect to the control grid 49 which is the point of minimum current. The anti-resonant impedance of the cathode-grid circuit, with the two resonators tuned to the same resonant frequency, then acts as a resistance connected in series with the capacitance between the coupling wire and the anode. The voltage drop across such a resistance is, of course, shifted by roughly 90° in phase, relative to the high-frequency voltage between the anode and accelerating grid. The voltage drop across this resistance is effective to

maintain the oscillations in the cathode resonator with the field of the anode resonator rising to a maximum in the direction aiding movement of the electrons 90° behind the field in the anode resonator. The amount of the phase shift is generally considered as being about 90° though it may be as little as 45° or as much as 135°.

To tune the anode resonator 5, a short-circuiting contact unit 61 is provided, surrounding the reentrant protuberance 11 above the anode 33 and within the annular space between the side wall of the protuberance 11 and the outer side wall 9 of the anode resonator. The contact unit 61 comprises a plurality of contactors 63 each of which extends across the annular space and has a sliding contact with the side wall of the reentrant protuberance 11 and the outer wall 9 of the resonator. The contactors 63 are arranged radially about the reentrant protuberance 11 and are positioned to interconnect a plurality of points on the two walls. The details of an individual contactor are set forth in the copending application of R. L. Treuthart, Serial No. 583,295, filed March 17, 1945, now Patent No. 2,456,902.

Each contactor 63 comprises a flexible metallic bellows 64 of a generally cylindrical shape, with contact buttons 65 and 66 mounted within and at opposite ends and completely closing the bellows. A passageway for cooling-fluid is provided through the interior of the bellows structure from an inlet 67 in one contact button 66 to an outlet 69 in the other. A cooling-fluid, such as water, is supplied to the bellows structure under pressure through an inlet pipe 71 and an outlet pipe 73 connected to inlet and outlet manifolds 75 and 77, respectively, which, in turn, are adapted to be connected to a source of the cooling-fluid through a pair of conduits 79 and 81. The manifolds 75 and 77 are mounted on a flat ring structure 83, suspended from an adjusting arm 85 on the outside of the anode resonator by a pair of hollow pipe supports 87 and 89 through which conduits 79 and 81 extend. The contactors 63 are supported by the inlet and outlet pipes 71 and 73 and are held in position by a second flat ring structure 91 mounted directly above the contactors 63 and suspended from the first ring structure 83 by posts 93, the second ring structure 91 having slots 95 therein through which the inlet and outlet pipes extend.

When cooling water under pressure is supplied to the contactors 63, it causes them to be expanded so that the contact buttons 65 and 66 engage and form a good pressure contact with the side wall of the protuberance 11 and the outer side wall 9 of the resonator. Consequently, these contactors 63 form an effective short circuit between the side wall of the protuberance and the outer wall of the resonator, and the resonant frequency of the resonator depends upon the location of the short circuit.

To change the location of the short circuit, the supporting arm 85 located outside the resonator is threadedly engaged with a rotatable shaft 97 supported vertically on top of the tube. This shaft 97 may be conveniently rotated by means of a handcrank 99 and gears 101, as illustrated. When the shaft 97 is rotated, the arm 85 is moved up or down, depending upon the direction of rotation of the shaft. Such movement of the arm 85 is obviously effective to move the supports 87 and 89 and the contact unit 61 one way or the other, in a direction substantially parallel to the axis of the tube. As a result, the location of the

short circuit in the anode resonator may be varied, to tune the resonator.

The pipe supports 87 and 89 extend through the top of the anode resonator with a sliding fit, permitting the supports to be moved relative to the resonator for tuning purposes as described. The anode resonator and the cathode resonator are adapted to be evacuated by means of a vacuum pump, not shown, to be connected across a flanged opening 103 in the anode resonator. To aid such evacuation, vacuum-tight seals 105 are provided about the supports 87 and 89. The seals 105 are of the type known as a "Wilson seal" and include a tight fitting fiber or leather ring 106 about each support which is clamped at its outer edges in a stationary clamp 107 mounted on top of the tube. Such a seal permits the supports to be moved or slid therethrough while maintaining a vacuum within the resonator. Of course other types of seals permitting movement of the supports, such as bellows, may be used if desired.

As set forth in the aforesaid copending application of Treuthart, the contactors insure a good electrical connection between the side wall of the protuberance and the outer side wall of the resonator. The cooling fluid is supplied through the contactors under pressure and serves not only to cool the contactor, a necessary operation because of the heat developed by current conducted through the contactor, but also to expand the contactor axially into pressure engagement with the walls. Consequently a good short-circuiting connection is maintained while the contact unit is moved back and forth for tuning even though the surfaces of the walls might be irregular and non-uniformly spaced. It is apparent that sliding contactors of a different construction may be used in the contact unit if each one has a means for insuring pressure engagement with the walls as well as a provision for cooling.

A coupling loop 109 is provided within the anode resonator and is connected to a coaxial transmission line 111 of the usual type to extract power from the resonator. Cooling pipes 112 may also be provided to carry cooling fluid about the outer wall of the tube.

Direct-current voltages are impressed on the anode, cathode and grids of the tube, as shown schematically in Fig. 1. The anode 33 and accelerating grid 51 are grounded and are connected to the positive terminal of a suitable direct-current voltage source 113 illustrated as a battery. The negative terminal of the voltage source 113 is connected through a wire 115 and the leads within the cathode mounting 21 to the cathode 19. The negative terminal of the voltage source 113 is also connected through a resistor 117 to the control grid 49. An alternating voltage, for supplying heating current through the filament wires 17, is provided from a source 119 through a suitable transformer 121.

To operate the tube, the two resonators 5 and 7 are first tuned to substantially the same frequency, by means of the handwheel 29 and the handcrank 99. The direct-current voltages, as well as the filament-heating current, are then applied to the elements in the tube and oscillations are initiated, building up in the well-known manner. The control grid 49 is initially at the same potential as the cathode 19, but, as the oscillations build up, current through the resistor 117 causes the control grid 49 to become negative with respect to the cathode 19 and so restricts the liberation of electrons to the peak portion of the half-cycle in which the field within the cathode

resonator 7 is in a direction to aid the movement of the electrons. The electrons acquire considerable energy from the high-frequency field of the cathode resonator, as well as the direct-current voltage fields. With the approximately 90° phase displacement between the electromagnetic fields of the anode and cathode resonators, the electromagnetic field of the anode resonator is in a direction opposing the motion of the electrons while they pass therethrough. As a result, the electrons give up energy to the field of the anode resonator producing the oscillations therein. The spacing of the elements is such that the electrons reach the anode during, or near the end of, the half-cycle in which the field of the anode resonator opposes their motion. As previously indicated, some of the power generated in the anode resonator is fed back to the cathode resonator, while the remaining power is fed to the output transmission line.

It is to be noted that, with the anode and accelerating grid at the ground potential, the tube may be mounted without special difficulty involving insulation of these parts. For the same reason, the anode resonator may be ruggedly constructed and very little, if any, power escapes through openings in the resonator. In addition, the output transmission line is also at ground potential and its connection to other suitable apparatus is facilitated. As previously indicated, the anode and accelerating grid may now be maintained at substantially the same direct current potential in view of my discovery that a resonatron tube may be operated under such conditions. Formerly it was believed necessary to maintain the anode and accelerating grid at different direct current potentials. Various reasons were advanced for this belief including the theory that such potential difference was necessary to keep the electron path clear of ions and to keep the interaction space in the anode resonator free of secondary electrons. Some of the early experiments with resonatron tubes seemed to support this former contention but my recent experiments have shown it unnecessary to have the anode and accelerating grids at different potentials.

It is to be noted that the tuning of a reentrant cavity resonator by means of short-circuiting connections between the side wall of the protuberance and the outer side wall of the resonator introduces many difficult problems which are solved by the structure described. These difficulties involve the provision of some means for connecting a plurality of points on the wall of the protuberance with a plurality of points on the outer wall of the resonator with means for adjusting or changing the points of interconnection while maintaining a vacuum within the resonator and supplying cooling fluid to each connector.

While the tuning arrangement described herein is slightly more complicated than that employed in the earlier resonatron tubes, it is worthwhile because of the decrease in the Q of the anode resonator afforded thereby. The variable capacitor at the end of the protuberance in the earlier tubes necessitated three quarters of a wave length between the capacitor and the other end of the resonator to provide a maximum electromagnetic field at the electron path. However, the present tuning arrangement necessitates only one-half or two quarters of a wave length within the resonator to provide the same maximum field at the electron path. Since each quarter wave length stores up a certain amount of energy, it is

then apparent that with the present system only two-thirds as much energy is stored. Consequently the Q is lowered by more than thirty percent.

Although I have shown and described a preferred embodiment of my invention, I am aware that many modifications thereof are possible, without departing from the spirit of the invention. I do not intend, therefore, to limit my invention to the specific embodiment disclosed.

I claim as my invention:

1. A cavity resonator comprising a hollow conductive body with an elongated conductive member extending within the body from and connected to an end thereof defining a ring-like space between the member and a portion of the body longitudinally coextensive with said member, short-circuiting contact means surrounding said member within said space and comprising a plurality of flexible contactors mounted about said member and extending transversely across said space and having sliding pressure contact with both said member and said body portion, and a unitary element slidably mounted within said body supporting said contactors, and adjustable means connected to said element for moving said unitary element to effect movement of said contactors lengthwise of said member to tune the resonator.

2. A cavity resonator comprising a hollow conductive body with an elongated conductive member extending within the body from and connected to an end thereof defining a ring-like space between the member and a portion of the body longitudinally coextensive therewith, short-circuiting contact means surrounding said member and including a plurality of flexible contactors mounted substantially radially about said member and extending across said space, said contactors having sliding pressure contact with both said member and said body portion, and a ring-like plate within said body supporting said contactors, supporting means for said plate mounted on the outside of said body and including a support extending through an opening in the body and connected to said plate, and adjustable means connected to said support and operable from outside said body for moving said support to effect movement of said plate and contactors lengthwise with respect to said member to tune the resonator.

3. A cavity resonator comprising a hollow, conductive body with an elongated conductive member extending within the body from and connected to an end thereof, short-circuiting contact means within the body interconnecting the member and another portion of the body, said contact means having a sliding pressure contact with said member and body portion and having a passageway therethrough for cooling fluid, conduit means connected to said passageway and extending outside said body for connection to a source of cooling fluid, and adjustable means connected to said contact means for moving the contact means to tune the resonator.

4. A cavity resonator comprising a hollow conductive body with an elongated conductive member extending within the body from and connected to an end thereof defining a ring-like space between the member and a portion of the body longitudinally coextensive therewith, short-circuiting contact means surrounding said member and including a plurality of contactors mounted about said member and extending across said space, each of said contactors being

flexible and having sliding pressure contact with said member and said body portion, and also having a passageway for cooling fluid, conduit means connected to all of said passageways and extending outside said body for connection to a source of cooling fluid, and adjustable means connected to said contact means for moving said contact means lengthwise of said member to tune said resonator.

5. A cavity resonator comprising a hollow conductive body with an elongated conductive member extending within the body from and connected to an end thereof defining a ring-like space between the member and a portion of the body longitudinally coextensive therewith, short-circuiting contact means surrounding said member and including a plurality of contactors mounted about said member and extending across said space, each of said contactors having sliding pressure contact with said member and said body portion, and also having a passageway for cooling fluid, and a ring-like plate within said body supporting said contactors, hollow supporting means for said contact means mounted on the outside of said body and extending and slidably through an opening in the body and connected to said plate, said hollow supporting means having conduits therein communicating with said passageways and adapted to be supplied with cooling fluid from a source outside said body, and adjustable moving means operable from outside said body for moving said hollow supporting means to effect movement of said contactors lengthwise with respect to said member to tune the resonator.

6. A resonator according to claim 5 in which said supporting means also includes a rotatable shaft mounted outside said body and extending in the same general direction as said member and an arm connected to said hollow supporting means and threadedly mounted on said shaft, and in which said moving means includes means for rotating said shaft whereby said arm is moved to move said hollow supporting means.

7. A cavity resonator comprising a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, contact means within said space having a sliding pressure contact with said member and body portion in a plane substantially parallel to said vector and providing a short-circuit interconnection therebetween substantially in said plane, said contact means also having a passageway therethrough for cooling fluid, conduit means connected to said passageway and extending outside said body for connection to a source of cooling fluid, and adjustable means connected to said contact means for moving the contact means to tune the resonator.

8. A cavity resonator comprising a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, contact means surrounding said member and including

a plurality of contactors mounted about said member and extending across said space, each of said contactors being flexible and having a sliding pressure contact with said member and body portion in a plane substantially parallel to said vector and providing a short-circuit interconnection therebetween substantially in said plane, the contacts of all of said contactors being in substantially the same plane, each of said contactors also having a passageway for cooling fluid therein, conduit means connected to all of said passageways for connection to a source of cooling fluid, and adjustable means connected to said contact means for moving it lengthwise of said member to tune said resonator.

9. An electronic tube comprising a cavity resonator including a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, an anode mounted at one side of said space, a cathode mounted at a radially opposite side of said space and adapted to project electrons through said space along a path from said cathode to said anode, contact means within said space, said path being between said body end and contact means and said contact means having a sliding pressure contact with said member and body portion in a plane substantially parallel to said vector and providing a short-circuit interconnection therebetween substantially in said plane, and adjustable means connected to said contact means for moving it to tune the resonator.

10. An electronic tube comprising a cavity resonator including a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, an anode mounted at one side of said space, a cathode mounted at a radially opposite side of said space and adapted to project electrons through said space along a path from said cathode to said anode, contact means within said space, said path being between said body end and contact means and said contact means having a sliding pressure contact with said member and body portion in a plane substantially parallel to said vector and providing a short-circuit interconnection therebetween substantially in said plane, said contact means also having a passageway for cooling fluid, conduit means connected to said passageway and extending outside said body for connection to a source of cooling fluid.

11. An electronic tube comprising a cavity resonator including a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, an anode mounted at one side of said space, a cathode mounted at a radially opposite side of said space and adapted to project electrons through said space along a path from

5 10 15 20 25 30 35 40 45 50 55 60 65 70 75

said cathode to said anode, contact means surrounding said member within said space, said path being between said body end and contact means and said contact means including a plurality of contactors mounted about said member and extending across said space, each of said contactors being flexible and having a sliding pressure contact with said member and body portion in a plane substantially parallel to said vector and providing a short-circuit interconnection therebetween substantially in said plane, the contacts of all of said contactors being in substantially the same plane.

12. An electronic tube comprising a cavity resonator including a hollow conductive body with an elongated conductive member extending within the body from and connected to an end thereof defining a ring-like space between said member and a portion of the body longitudinally coextensive therewith, said body being adapted to have electromagnetic field oscillations established within said space having a substantially radial electric vector, an anode mounted at one side of said space, a cathode mounted at a radially opposite side of said space and adapted to project electrons through said space along a path from said cathode to said anode, contact means surrounding said member within said space, said path being between said body end and contact means and said contact means including a plurality of contactors mounted about said member and extending across said space, each of said contactors being flexible and having a sliding pressure contact with said member and body portion in a plane substantially parallel to said vector and providing a short-circuit interconnection therebetween substantially in said plane, the contacts of all of said contactors being in substantially the same plane, each of said contactors also having a passageway for cooling fluid therein, conduit means connected to all of said passageways for connection to a source of cooling fluid.

13. An electronic tube of the resonatron type comprising a pair of cavity resonators each comprising a hollow, conductive shell, an anode mounted in and secured to one of said shells, a cathode mounted in the other shell, said shells being mounted adjacent each other and having adjacent portions each with a grid therein whereby electrons may pass along a path from the cathode to the anode through the grids, and facilities for establishing in said shells electromagnetic field oscillations having an electric vector between the cathode and anode in the same direction as said path, said facilities including circuit connections to impress direct current voltages between said anode, grids and cathode such that said anode is at ground potential and said cathode at a negative potential, the grid in said one shell being conductively connected to said anode by said one shell whereby said grid in said one shell and said anode are maintained at ground potential.

14. An electronic tube of the resonatron type comprising a first cavity resonator including a first hollow conductive body with an elongated conductive member extending within the body from and connected to an end thereof defining a ring-like space between the member and a portion of the first body longitudinally coextensive therewith, a ring-like anode mounted within said space, a second cavity resonator including a second hollow, conductive body, a cathode mounted within said second body, said first and second bodies being mounted adjacent each other and

having adjacent walls with grids therein, the position of said bodies and grids permitting electrons to pass along a path from said cathode to said anode through said space, each of said bodies being adapted to have electromagnetic field oscillations established therein having an electric field vector between the cathode and anode in the same direction as said path, said anode, grids and cathode being adapted for connection to external circuit means to impress direct current voltages thereon with said anode and the grid of the first body at substantially the same direct current voltage, short-circuiting contact means extending across said space interconnecting points on said member and said first body portion, said contact means having sliding pressure contact with said member and first body portion, and adjustable means connected to said contact means and extending outside said first body for moving said contact means longitudinally of said member to change the points of interconnection and thereby tune the first resonator.

15. An electronic tube of the resonatron type comprising a first cavity resonator including a first hollow conductive body with an elongated substantially cylindrical hollow conductive member extending within the body from and connected to one end thereof defining an annular space between the member and a portion of the first body longitudinally coextensive therewith, an annular anode mounted within said annular space and connected to said first body portion, said member having a side wall with a first grid therein opposite said anode, a second cavity resonator including a second hollow conductive body, a substantially cylindrical cathode mounted within said second body, said second body being substantially cylindrical and mounted within said member with a side wall adjacent the side wall of the member having a second grid therein adjacent the first grid whereby electrons may pass along generally radial paths from the cathode to the anode, each of said bodies being adapted to have electromagnetic field oscillations established therein having substantially radial electric field vectors between the cathode and anode, said anode, grids and cathode being adapted for connection to external circuit means to impress direct

5 current voltages thereon, the first grid being conductively connected to said anode by said first body whereby said first grid and said anode are maintained at substantially the same direct current voltage, short-circuiting contact means extending across said annular space interconnecting points on said member and said first body portion, said contact means having sliding pressure contact with said member and first body portion, and adjustable means connected to said contact means and extending outside said first body for moving said contact means longitudinally of said member to change the points of interconnection and thereby tune the first resonator.

10 15. An electronic tube apparatus comprising a pair of cavity resonators each comprising a hollow, conductive shell, an anode mounted in one of said shells, a cathode mounted in the other shell, said shells being mounted adjacent each other and having adjacent portions each with a grid therein whereby electrons may pass along a path from the cathode to the anode through the grids, and external circuit connections from said anode, grids, and cathode, said connections from said cathode and from said grid adjacent said cathode terminating in a common point, there being an impedance connected between said point and said grid adjacent said cathode.
